(57) **CLAIM**

The ornamental design for a manifold, as shown and described.

DESCRIPTION

FIG. 1 is a perspective view of a manifold showing our new design.

FIG. 2 is another perspective view thereof.

FIG. 3 is another perspective view thereof.

FIG. 4 is another perspective view thereof.

FIG. 5 is another perspective view thereof.

FIG. 6 is another perspective view thereof.

FIG. 7 is a front view thereof.

FIG. 8 is a rear view thereof.

FIG. 9 is a left side view thereof.

FIG. 10 is a right side view thereof.

FIG. 11 is a top view thereof; and,

FIG. 12 is a bottom view thereof.

The broken lines are for the purpose of illustrating portions of the manifold and form no part of the claimed design.

The dot-dash broken lines represent an unclaimed boundary and form no part of the claimed design.
